UNITED STATES PATENT OFFICE.

STEPHEN W. JONES, OF SOUTH UNION, MAINE.

DESIGN FOR A DOOR-HANGER.

SPECIFICATION forming part of Design No. 12,897, dated April 18, 1882.

Application filed March 7, 1882. Term of patent 14 years.

To all whom it may concern:

Be it known that I, STEPHEN W. JONES, of South Union, Knox county, Maine, have invented a Design for Door-Hangers, of which 5 the following is a specification.

My invention is a design for a door-hanger, whereby a neat and symmetrical shape is imparted to the structure without detracting from the strength or efficiency.

- 10 In the drawing the improved hanger is illustrated in perspective, A being a back plate or securing-plate, having side and end ears, *a a b*, perforated for the passage of the securing-screws. The plate A is widened at the upper 15 end until it corresponds to the length of the side piece of the yoke C, and through the lat-

ter and through the back plate passes the pin on which turns the pulley D.

I claim—

The design for a frame for a door-hanger, 20 the same consisting of a back piece having ears *a a b* at one end and widened at the other, and a yoke, C, at the widest end, substantially as set forth.

In testimony whereof I have signed my name 25 to this specification in the presence of two subscribing witnesses.

STEPHEN W. JONES.

Witnesses:

AUGUSTUS VAUGHAN,
EDWARD C. JONES.
